ATTORNEY.*

UNITED STATES PATENT OFFICE.

ALFRED WEED, OF PHILADELPHIA, PENNSYLVANIA.

MACHINE FOR STRIPPING FILE-BLANKS.

SPECIFICATION forming part of Letters Patent No. 287,072, dated October 23, 1883.

Application filed February 18, 1882. (No model.)

To all whom it may concern:

Be it known that I, ALFRED WEED, of the city and county of Philadelphia, in the State of Pennsylvania, have invented certain new and useful Improvements in Machines for Finishing File-Blanks. The following is a specification of said improvements, reference being had to the accompanying drawings, wherein—

Figures 1 and 2 represent, respectively, side 10 and end elevations of a machine embodying my invention; Fig. 3, a top or plan view thereof; and Fig. 4, a view in perspective, and on an enlarged scale, of certain details thereof.

For the production of an accurate and uniform cutting-surface upon a file it is of the utmost importance that the surfaces of the blank whereon the teeth are to be cut should be true, and that a smooth and even finish should be given thereto. Such machines as have heretofore been used for the finishing or "stripping" 15 of file-blanks have been open to the objection that inequalities in the edge of the stripping-tool or variations in the hardness of different portions thereof produced grooves or ridges in 20 the surface of the blank. Furthermore, owing to the direction of the lines of cut of the stripping-tool, it has been found that a hard or "glazed" surface is produced upon the blank, 25 which renders the cutting of the teeth thereon difficult.

It is the object of my present invention to remedy these defects; and to that end my improvements consist in giving to the blank, while under the action of the reciprocating 30 stripper, a radial motion in the same plane with, but across, the lines of reciprocation. Thus not only does each portion of the stripper traverse the entire surface of the blank, but the lines of cut are compelled to intersect 35 each other in a peculiar manner, being resultants of the two movements. I have found in practice that the blanks stripped in this manner not only have a true and uniform finish, but that the surface is not glazed, and is much more 40 easily worked into teeth than where the stripping has been performed mechanically by the methods hitherto employed, or even by hand. I also suspend the work-plate and the tool 45 upon bearings which permit them to rock freely in directions at right angles to one another, and thus to automatically level them-

selves, and obviate any tendency toward irregular cutting.

In the accompanying drawings, A A are the 55 housings, upon the top of which are mounted the horizontally-oscillating frames B', each pivoted at R. Vertical standards B, upon each of the frames B', are threaded to receive supporting-screws H, the pointed ends of which are inserted into seats in the ends of the work-plate G. The work-plate G is a flat plate of 60 metal having a clamping-screw, J, which secures the tang of the file-blank F and holds it firmly in position. The work-plate with the blank is thus free to rock laterally upon 65 the points of suspension. The overhanging free ends of the frames B' rest upon a horizontal plate, X, and are received between lugs z z' thereon. The plate X is supported by the revolving horizontal disk W, upon the face of 70 which is a wrist-pin, Y, engaging in a lateral slot, U, of the plate X. The longitudinal slots U' (see Fig. 3) in the plate X receive the guide-pins Y', which project from the housings. (See Fig. 2.) The plate X is thus free to be moved 75 longitudinally by the revolution of the disk W and pin y, and by its motion to oscillate the frames B' upon their pivots R. The shaft of disk W is mounted upon a bracket projecting 80 from the housings, and is provided at its lower end with a worm-wheel, V, engaging with a worm or screw, T. The worm-shaft is rotated from the driving-shaft of the main pulley M by means of the pulleys P P' and belt Q. A vertical lever, T', pivoted to the base of 85 the machine at N, is connected by means of the arm K with an adjustable crank-pin secured in a slot on the disk L, mounted upon the main driving-shaft. The upper end of the lever T', which projects between and above the frames 90 B', is formed into a cross-head, C, to which are secured the carriers D. Transverse semi-cylindrical seats are formed in the lower surface of the latter, in which the correspondingly-shaped holders D' of the finishing tools or 95 strippers E fit snugly. Motion-offsets upon the ends of the tool-holders D' prevent their longitudinal displacement; but they are free to rock laterally, the offsets being provided with slots s', through which the headed pins s 100 project, so as to maintain the holders in their seats, while permitting their partial rotation.

The operation of my machine is as follows: The unfinished file-blank F being secured upon the work-plate G by inserting the tang beneath the screw-clamp J, the driving-shaft is 5 rotated, and the lever T' reciprocates rapidly back and forth, causing the stripper E to operate upon the face of the blank. At the same time the rotation of the screw T actuates very slowly the revolving disk W, whose crank-pin 10 Y effects the reciprocation of the plate X, and thus slowly oscillates the frames B' radially upon the pivots R and across the line of motion of the stripper E. The lines of cut are therefore 15 the resultants of these combined movements, and each portion of the cutting-edge acts upon the entire surface of the blank, thus producing a most perfect and uniform finish. Furthermore, the stripper and the blank, being free to rock upon horizontal axes at right angles to one another, adjust themselves automatically to the proper plane, and thus insure the parallelism of the sides.

I am aware that it is not new to move the file-blank in a direction whose line is approximately that of a figure 8, the stripper being stationary during such movement. In this mode of operation, however, the stripper retraces its exact path at each complete reciprocation, and the production of grooves and ridges is not avoided, the only result being that they take the form of a figure 8 instead of being straight and parallel, as in the other old forms of stripping devices. The main object 35 of my invention being to so move the stripper and the blank relatively to one another that the resultant lines of cut made by any given point upon the stripper shall be constantly-varying curves, and that such point shall not retrace its path during the stripping of any 40 one blank, it is obvious that the devices first referred to as old differ in mode of operation and result, as they also do widely in structure, from my improvements. I therefore disclaim all devices whose operation is such that a given 45 point upon the stripper will be caused to retrace its path upon a blank or to form thereon a series of parallel and straight lines.

In the instance shown I have represented the machine as provided with two strippers and work-frames, so as to simultaneously finish two blanks. It is obvious, however, that the number may be varied—as, for instance, by attaching to the other end of the cross-head C a second set of strippers and projecting the frames B' beyond the pivot R, in order to carry 55 the necessary work-plates at their other ends.

It is also obvious that the mechanism for producing the independent movements of the stripper and the work-plate may be varied greatly without changing the principle of my 60 invention. Thus the stripper may be moved radially in a plane in which the file-blank is caused to reciprocate and the resultant lines of cut still be varying curves. I therefore do not limit my claim to the precise mechanism 65 shown and described; but

I desire to secure by Letters Patent—

1. The combination of the stripper, the work-frame, and mechanism whereby one is reciprocated in a given plane while the other is oscillated radially in said plane across the lines of reciprocation, substantially in the manner and for the purposes specified.

2. The combination of a reciprocating stripper rocking freely in its seat, and a work-plate 75 oscillating radially across the line of reciprocation and rocking freely in a direction at right angles to the axis upon which the stripper rocks, substantially as and for the purposes set forth.

3. The combination of the driving-shaft, the lever T', and tool-carrier reciprocated thereby, and the worm-wheel, screw, and crank-disk, and pivoted frame B', oscillated by said crank-disk, the whole arranged and operating substantially as set forth, whereby a rapid reciprocation of the tool-carrier and a continuous slow radial oscillation of the work across the 85 line of such reciprocation are effected.

ALFRED WEED.
